(57) **CLAIM**

The ornamental design for a chain, as shown and described.

DESCRIPTION

FIG. 1 is a perspective view of a chain showing my new design;

FIG. 2 is another perspective view thereof;

FIG. 3 is a front elevation view thereof;

FIG. 4 is a back elevation view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view thereof; taken from encircled portion 9 in FIG. 1;

FIG. 10 is an enlarged view thereof; taken from encircled portion 10 in FIG. 1;

FIG. 11 is an enlarged view thereof; taken from encircled portion 11 in FIG. 1;

FIG. 12 is an enlarged view thereof; taken from encircled portion 12 in FIG. 2; and,

FIG. 13 is an enlarged view thereof; taken from encircled portion 13 in FIG. 2.

The broken lines in the drawings represent portions of the chain and form no part of the claimed design. The chain is shown with a symbolic break in its length. The appearance of any portion of the chain between the break lines forms no part of the claimed design.

1 Claim, 13 Drawing Sheets
